UNITED STATES PATENT OFFICE.

ALBERT G. DAVIS, OF SCHENECTADY, NEW YORK, ASSIGNOR TO GENERAL ELECTRIC COMPANY, A CORPORATION OF NEW YORK.

REGENERATIVE SYSTEM.

SPECIFICATION forming part of Letters Patent No. 714,157, dated November 25, 1902.

Application filed March 29, 1902. Serial No. 100,573. (No model.)

To all whom it may concern:

Be it known that I, ALBERT G. DAVIS, a citizen of the United States, residing at Schenectady, in the county of Schenectady, State of New York, have invented certain new and useful Improvements in Regenerative Systems, of which the following is a specification.

My invention relates to a system of control especially adapted for restoring energy to the source of supply in the braking of electrically-operated bodies of considerable mass, such as railway-trains, elevators, hauling plants, and the like.

In braking by means of ordinary brakes the kinetic energy which is stored in the moving body is uselessly destroyed. A large percentage of the energy which is thus ordinarily wasted may be recovered and returned to the line or source of power by the use of the invention herein described.

The system which I have now devised permits of the location of the translating device at a fixed point distant from or adjacent to the line of travel of the moving body—such, for instance, as at a station on the line of railway instead of on the vehicle—and also dispenses with storage batteries and overcomes the difficulties which have been experienced by their use.

My invention as herein described and illustrated relates to the operation of electric motor cars or trains, and is particularly adapted for use with the modern high-speed equipments, in which a number of electric motors are employed. It has for its principal object the return to the supply-line of a part of the energy taken up by the car or train in its ordinary operation—that is, when the car has attained its normal running speed and it becomes necessary to stop at a station. This slowing down or braking is accomplished without the operation of the mechanical braking device usually carried by the car and is maintained until the car has been brought almost to a full stop, at which time the said mechanical braking device may be operated.

A further application of my invention is in starting a train from a station without the use of the resistance ordinarily carried by the car for the purpose of varying the elec-

tric force impressed upon the motor-circuit.

In the preferred manner of carrying my invention into effect I combine with the operating system a combination dynamo-electric machine located at a station on a line of railway or at a fixed point distant from the line of travel of the moving body or vehicle, so constructed that it will transform the constantly-diminishing electromotive force generated by the motors of the moving vehicle, acting as generators, into a practically-constant electromotive force counter to and greater than that of the line, so that a current will continue to flow from the generators on the cars to the line until the car is brought almost to a full stop. This is accomplished by so connecting the fields of the individual machines or elements constituting the combination set to a rheostat operated by means controlled by the operator on the car that the field of one machine or element is increased as the field of the other machine or element is decreased. The armatures of these machines are mechanically connected together and also mechanically connected to a third armature operating in a practically-constant field. The function of the last-mentioned machine of the combination is to maintain the fields of the motors on the car practically constant, independent of the line-voltage, while said motors are acting as generators; and my invention further consists of means for so connecting said machine with the fields of the said motors that such a constant field as above described will be maintained.

In a modified system embodying my invention I make use of a motor-generator set located at a fixed point or station, the motor being an alternating-current motor, taking current either directly from the main line or through a transformer. The field of the direct-current generator is varied by electrically-operated means located at the fixed point and controlled from the moving vehicle. The means for maintaining a constant field for the car-motors when acting as generators comprises a shunt-wound generator mechanically coupled to the motor-generator. A storage battery located either at the station or on the

car or an independent dynamo-electric machine might be used for this purpose.

A further modified system embodying my invention comprises means for varying the ratio of transformation of the transformer supplying current from the line to a rotary converter. In this system the fields of the motors carried by the moving vehicle are maintained practically constant, as is also the field of the rotary converter, by means of a smaller auxiliary rotary converter taking current through an independent transformer directly from the line.

My invention may also be used in starting a car or train. When thus used, it comprises means for so varying the fields of two of the machines constituting the combination set, or for varying the field of the direct-current side of the motor-generator, or for varying the ratio of transformation of the transformer supplying current from the line to the rotary converter that a gradually-increasing electromotive force will be impressed across the armatures of the motors carried by the car, which 25 motor-armatures are operating in practically-constant fields maintained by either the third machine of the combination set above referred to, or by an auxiliary machine located at the same point at which the translating 30 device is located, or by a battery carried by the car. In this manner the said motors may be brought up to speed without the use of resistances or other starting devices carried by the car, thus accomplishing a great saving in 35 the energy supplied by the line.

My invention will be better understood from the following description, taken in connection with the accompanying drawings, while its scope will be pointed out in the appended claims.

Referring to the drawings, Figure 1 is a diagrammatic representation of one embodiment of my invention as applied to a train system in which the motors carried by the cars are arranged to restore energy to the line through the agency of a translating device located at the station as the train is being brought to rest at said station. Fig. 2 is a diagram of a modification in which means are provided for starting the train from the station through the agency of the translating device at the station. Fig. 3 is a vertical sectional view of one form of magnetic clutch which may be used in connection with my invention. Figs. 4 and 5 are diagrammatic representations of cars and motor connections. Fig. 6 is a diagrammatic representation of one system of station distribution and connections thereto. Fig. 7 represents an arrangement of contacts 60 which may be used on the controlling-switch which controls the connections between the translating device at the station and the propelling-motors in the system shown in Fig. 1. Fig. 8 is a diagrammatic representation of a modified system in which a motor-generator is used and in which means are provided for varying the field of the direct-current side of

said motor-generator, and Fig. 9 represents diagrammatically another modified system. In this case the ratio of transformation of the transformer supplying current from the line to a rotary converter is varied by electrically-operated means controlled from the moving vehicle.

Referring now to Fig. 1, A represents the main source of supply of a polyphase current to the line L. T is a transformer, and B a rotary converter of ordinary construction located at any suitable point or points along the line, preferably at the stations. From the direct-current side of the rotary converter leads the feeder F, which is connected at intervals through the conductors F' to the third rail or trolley-wire R', from which the current used by the cars, which are operating on the track R R, is collected in the ordinary manner. The system of ground or rail return is here shown, but a complete metallic circuit might be used as well. The motors carried by the cars may be operated by the usual method of series-parallel control or any other well-known method. The motors M' M² are shown at X on the right of Figs. 1 and 2, connected in their normal running connection for maximum speed—that is, in parallel to the third rail R' through the conductor 4^a. At each station E (indicated by dotted lines) and connected between the positive brush of the direct-current side of the rotary converter and ground is a composite machine C, comprising three armatures a³ a⁴ a⁵ and three field-magnet systems f³ f⁴ f⁵. The field-windings of the upper two of these machines or elements are inversely controlled by means of a controlling-switch Rh, which is operated by the motor M.

As shown in Fig. 1, additional contact-rails 1, 2, and 3 are provided at each of the stations. Trolley-shoes adapted to engage these conductors or contact-rails are carried by the cars. When the car or train reaches the station, so that the shoes engage with these conductors, the connections are made such that the fields f' and f² of the motors M' and M² will be separately excited from the lower machine of the combination C and such that the armatures a' and a² will be connected in multiple across the terminals of the middle machine of the combination C. This arrangement is indicated diagrammatically at Y, Figs. 1 and 2. By means of a switch on the car—such, for instance, as s' on the car V, (shown in dotted lines in Fig. 4, in which figure the wheels of the car are represented by w)—current may be supplied to the motor M through the conductor 3. In practice these connections may be readily made by the controller carried by the car in such a manner as shown in Fig. 7, which will be described farther on.

In the system shown in Fig. 1 the motor M is so connected electrically that it will run in one direction only and is connected with the controlling switch-arm b by means of a worm

and gear or other mechanical connection and a magnetic clutch D, one form of which is shown in Fig. 3 and which will now be described. Loosely mounted on the spindle g and capable of rotary movement, but incapable of vertical movement thereon, is a magnet k, which carries the coil m and is rigidly attached to the handle b. Splined to the spindle g and capable of vertical movement thereon is the armature h, which is normally kept away from the magnet k by means of the spring d'. Upon the energization of the magnet k the armature h is attracted and the arm b is constrained to move with the spindle g. The arm b is limited in its movement by the stop s and returns to its normal position aided by the spring d, as soon as the magnet is deenergized.

If as the train comes into the station the switch or controller is properly placed, current will flow from the source of supply through the rail 3, conductor 16, field f, and armature a of motor M, conductor 17, coil m of magnetic clutch D, and conductor 18 to ground. The magnetic clutch will operate and the motor M will start and run the controlling-switch Rh in such a direction as to continually decrease the field f^4 of the middle machine of the combination C and increase the field f^3 of the upper machine of the combination C.

The operation of the system shown in Fig. 1 will now be described. Normally when no car is at the station current is received by the combination machine C from B through feeder F, conductor 9, and the armatures a^3 , a^4 , and a^5 in series to ground. The field-windings f^3 , f^4 , and f^5 are also connected between F and ground, as shown. Each machine of the combination is running light as a motor, and the sum of the counter electromotive forces generated by the armatures a^4 and a^5 nearly equals the impressed electromotive force of the line. When the car arrives at the braking distance from the station, so that the shoes carried by the car engage the rails shown between the track-rails, if the proper connections are made at the controller the motor M operates to reduce the field f^4 and increase the field f^3 at such a rate that the counter electromotive force produced by a^4 running as a motor always remains just a little less than the electromotive force impressed upon it by motors M' and M^2 running as generators. The middle machine then drives the upper and lower machines of the combination C as generators, and the field f^3 is increased at such a rate that the electromotive force across the terminals of the three machines is slightly greater than that of the line. In this manner current is forced through conductor 9, feeder F, back through the rotary converter B, which now runs as an inverted rotary and supplies current through the transformer T to line L. The current generated by the armatures a' and a^2 of the car-motors acting as generators flows through

the conductor 6, rail 1, conductor 7, armature a^4 , conductor 8, rail 2, conductor 5 to negative terminal of motor-armatures. Part of the current generated by the lower machine of the combination C flows through the armatures a^4 and a^3 , conductor 9 to line, and the remainder flows through the conductor 8, rail 2, conductor 5, fields f' and f^2 to ground at G, thus maintaining the field strength of M' and M^2 practically constant. By properly regulating the speed of the motor M and the divisions of the field-windings f^3 and f^4 , which are connected to the controlling-switch Rh, the above condition of the system may be maintained until the train comes nearly to a full stop, at which time the hand or air brakes may be applied.

In the system shown in Figs. 2 and 5 the motor M is so wound and connected that it may be reversed at the will of the operator on the car through the agency of a reversing-switch, such as is shown at S² in Fig. 5. This switch may be embodied as part of the controller or may be a separate switch located anywhere on the car or train. As will be seen, it is unnecessary in this system to use the magnetic clutch D, previously described in connection with the controlling-switch Rh, as the arm b is so connected as to be moved in either direction by the motor M. In this system an additional rail 4 is required, as is also an additional contact-shoe on the car. Current flowing through the rail 3 from the contact-shoe carried by the car through the conductor 16, field f, conductor 17, armature a to ground will cause the motor M to rotate in one direction. To reverse the motor M, a circuit is completed through the rail 4 from the additional contact-shoe carried by the car, conductor 19, field f in the opposite direction, conductor 17, armature a to ground. The operation of this system while the car is being brought to rest in front of a station is substantially the same as that of the system shown in Fig. 1, it being necessary to rotate the motor in the proper direction to reduce the field of the middle machine and increase the field of the upper machine of the combination C.

The system shown in Fig. 2 is also applicable as means for starting a car or train from a station and for bringing it up to such a speed that the motors on the car can be connected directly in their parallel position to the third rail or trolley R' without the use of a starting-resistance or intermediate series position of the controller. It will be remembered that when the car was brought to rest at the station the arm b of the controlling-switch Rh was in such a position that the field f^4 of the combination C was at its minimum strength, while the field f^3 was at its maximum strength. If now the motor M is reversed, so as to turn the arm b in the opposite direction, the field f^3 will be gradually diminished and the field f^4 gradually increased. The gradually-increasing electro-

motive force of a^4 , running as a generator, will be impressed upon the armatures a' and a^2 of motors M' and M^2 , while the fields f' and f^2 are constantly excited by a^5 , as before. In 5 this manner the motors M' and M^2 are gradually speeded up until the arm b strikes its stop s or the contact-shoes carried by the car leave the rails 1, 2, 3, and 4, at which time the motors are connected in parallel to the third 10 rail R' .

In Fig. 6 I have illustrated one system of distributing the stations E along the line L, using but one rotary converter for every three stations, the feeder F connecting these three 15 stations together. Of course any other combination of stations could be made, depending mainly upon the distance between stations. Such a system as here illustrated tends to more evenly distribute the current, which has 20 been fed back to the line of the cars, slowing down at the various stations by feeding it directly to cars which may be running at speed between stations instead of forcing it back through the rotary converter and through a 25 considerable length of line-wire.

In Fig. 7 I have shown a development of a controller C' which may be used in connection with the system shown in Fig. 1 and the connections therefor. 3^a to 13^a represent the 30 movable contacts commonly used in the series-parallel method of control. 1^c to 18^c represent the fixed contacts, and their connections with the motors M' and M^2 and the shoes t , t' , t^2 , and t^3 may be readily traced. 1^d to 18^d 35 represent a set of movable contacts, which are to be brought into communication with the fixed contacts above referred to in order to connect the motors M' and M^2 in such a relation as shown in Figs. 1 and 4 and furnish 40 power to the motor M. This last-named set of movable contacts may be mounted on the same cylinder on which the contacts 3^a to 13^a are mounted or may be separately and independently mounted. It must be understood 45 that I do not limit myself to the form of controller herein shown, for any set of switches which would act to make the connection required to carry out my invention would do just as well.

50 In the system shown in Fig. 8 instead of using the combination-machine C above described I employ a motor-generator comprising the alternating-current motor M^4 and the direct-current generator G^2 . The motor M^4 takes current directly from the main generator A through the line L and transformer T. Mounted on the same shaft which carries the armatures of M^4 and G^2 or mechanically connected thereto is a shunt-wound dynamo- 55 electric machine G' , one of the functions of which is to maintain the fields f' and f^2 of the motors M' and M^2 practically constant when the car or train is being braked at or started 60 from a station. The generator G' also furnishes current for the field f^7 of the generator G^2 and for the motor M, which is used to operate the arm b of the controlling-switch 65

Rh , which in turn controls the field f^7 of the generator G^2 . The controlling-switch Rh is so connected to the field f^7 and the resistance r' that as the field is gradually cut out a corresponding amount of the resistance r' is cut into the field-circuit, and vice versa when the field f^7 is gradually increased. The motor M is controlled by a switch S^3 , carried by 70 the car or train and may constitute part of the motor-controller or may be a separate switch located anywhere on the car or train. The track-rails are represented by R , R , the trolley or third rail by R' , and the auxiliary rails in front of the station by 2, 3, and 4, as before. The operation of this system is as follows: The current generated by the generator G^2 under normal conditions flows through the feeder F, conductor F', to sectional third 80 rail R' , through the motors in series or multiple connection to ground, and the auxiliary machine G' merely acts to assist the generator G^2 and maintain the field f^7 practically 85 constant. When the car or train arrives at 90 braking distance from the station—that is, when contact-shoes carried by the car engage the fixed rails 2, 3, and 4—the connection to the motors M' and M^2 are made as shown in Fig. 8 and the switch S^3 is thrown to connect the 95 motor M, so that it will operate to gradually reduce the field f^7 of the machine G^2 . The motors M' and M^2 are therefore run as generators, driven by the momentum of the car. The machine G^2 will run as a direct-current 100 motor with a gradually-diminishing counter electromotive force maintained just a little below that impressed upon it by the motors M' and M^2 , acting as generators, and the machine M^4 will run as a generator, feeding current into the line L through the transformer 105 T. The circuit through the motors M' and M^2 and the machine G^2 may be traced as follows: motor-armatures a' and a^2 , conductor 110 4^a, trolley or third rail R' , conductor F', feeder F, armature of G^2 , conductors 20 and 25, auxiliary rail 2, conductor 5 to armature a' and a^2 . The generator G' , one side of which is grounded, furnishes current to the fields of the car-motors through the following circuit: 115 conductors 30, 20, and 25, auxiliary rail 2, conductor 5, fields f' and f^2 to ground. The generator G' also furnishes current for the field f^7 through the following circuit: conductors 30 and 20, field f^7 , conductor 21, arm b 120 of controlling-switch Rh , conductor 22 to ground when the maximum field f^7 is in circuit and through conductors 30, 20, and 23, arm b , conductor 24, and resistance r' when field f^7 is entirely cut out. The resistance r' 125 is used to prevent a short circuit of the machine G' when the field f^7 is cut out by the controlling-switch Rh . The current for operating the motor M is taken from the auxiliary rail 2 and led to the circuits of the motor M in the same manner as shown in Fig. 2. 130

In the system shown in Fig. 9 the ratio of transformation of the transformer T is varied by varying the number of turns included in

its secondary. A transformer of the open-delta type is here shown and taps are led off from various points of the secondary winding, said points being symmetrically arranged with respect to its middle point. The leads from the taps are connected to the segments of the controlling-switch R_h , and the central point of the secondary is connected directly with the rotary converter B . The arm b is divided into two parts b' and b^2 , insulated from one another, and each of which is connected with the rotary converter B , as shown. This arm is operated by the motor M , which is controlled by the switch S^3 , carried by the car, in the manner previously described with reference to Fig. 2. By the means just described the electromotive force impressed upon the alternating-current side of the rotary converter B may be varied and the electromotive force given out by the direct-current side varied accordingly. In order to maintain the field f^3 of the rotary converter B and the fields f' and f^2 of the motors M' and M^2 practically constant, the auxiliary rotary converter B' , taking current directly from the line through the transformer T' , is used. When the car arrives at braking distance from the station, the connections on the car are made, as shown in Fig. 9, with one side of each of the armatures a' and a^2 grounded, while the other side remains connected with the third rail R' . One side of each of the fields f' and f^2 is grounded, while the other side is connected with the rail 2 through the conductor 26. In operation the current generated by the motors M' and M^2 , acting as generators, flows from the armatures which are grounded on one side, through conductor 4^a, third rail R' , conductor F' , direct-current side of rotary converter B to ground, driving the rotary reversed, with a gradually-diminishing counter electromotive force on the direct-current side, since the motor M operates to gradually cut out the secondary of transformer T , thus causing the alternating-current side of the rotary to generate an alternating current with a diminishing electromotive force slightly greater than the continually-diminishing electromotive force of the secondary of the transformer T , thereby returning energy to the line L . Part of the current from the direct-current side of the rotary converter B' flows through the conductor 28, rail 2, conductor 26, fields f' and f^2 to ground and part flows through conductor 28 and 29, field f^3 to ground. The current for operating the motor M is furnished by the rotary converter B' and is taken off from the rail 2, as before stated.

It will be understood in reference to the systems shown in Figs. 8 and 9 that the trolley or third rail should be divided up into sections and each section fed from the main line through a separate and independent power translating device. This is necessarily so, because the armatures of the motors carried

by the car are not disconnected from the third rail while the car is being brought to a standstill at or started from a station, and the potential varies throughout the whole length of the section of third rail R' , which is fed from the motor-generator or rotary converter.

On long and steep grades any one of the above-described translating devices might be located and adjusted and set by a controlling-switch, such as R_h , which when once set could not be changed except by some one located at that point and would not be affected by passing trains. By such means energy could be restored to the line when the train has attained a schedule speed beyond which it is not desired to go in descending the grade, and the braking effect of the motors acting as generators could be utilized on said grades. In such a case the motor M and the rails 3 and 4 would be unnecessary, and only the auxiliary rails 1 and 2 and in the systems shown in Figs. 8 and 9 only the rail 2 would be laid on said grade.

It will be further seen that in case one car should be standing at a station and another car should be approaching said station at full speed a collision would be prevented. In the systems shown in Figs. 1 and 2 this is due to the fact that the armatures of the motors on the car approaching the stations acting as generators would be short-circuited through the rails 1 and 2 and the motor-armatures of the car standing at the station, thus producing a tremendous braking effect and bring the moving car to a standstill almost instantly. In the systems shown in Figs. 8 and 9 the approaching car would be deprived of current or would receive current at an electromotive force below the normal electromotive force of the line if a car was at the station or within braking distance of the station.

In the use of my invention as applied to electric railways it will be found that the current requirements of a long line on which frequent stops are made will be materially reduced. The trains or cars which are coming to a station will supply a considerable percentage of the power needed to operate other trains which are still running at speed or are just starting.

Although I have shown and described an electric-railway system equipped with the proper apparatus for carrying out my invention, it must be understood that I do not limit myself to such a system, as the invention is equally applicable to variously electrically-operated devices which require frequent starting and stopping.

What I claim as new, and desire to secure by Letters Patent of the United States, is—

1. In a regenerative system, a moving body, a motor or motors operatively connected to said moving body, means for connecting said motor or motors to act as generators, and a translating device located at a fixed point capable of transforming the gradually-dimin-

ishing electromotive force produced by said motors acting as generators into a practically constant electromotive force.

2. In a regenerative system, a moving body, 5 a motor or motors operatively connected to said moving body and normally used for propelling said body, means for connecting said motors to act as generators, and a translating device located at a fixed point, normally connected to the source of power from which the 10 said motors are supplied and capable of transforming the gradually-diminishing electromotive force produced by said motors acting as generators into a practically constant electromotive force counter to that of the source 15 of power, whereby a current is caused to flow from the said motors acting as generators to the normal source of power.

3. In a regenerative system, a dynamo-electric machine carried by a movable vehicle, receiving power from a normal source of supply and normally operating to drive said vehicle, means for connecting said machine to act as a generator driven by the momentum of the 25 moving vehicle, means located at a fixed point along the line of travel of said vehicle for receiving the electromotive force produced by said dynamo-electric machine and for transforming it into electromotive force counter to 30 and greater than the impressed electromotive force of the said normal source of power, and means comprising rails located at said fixed point and contact-shoes carried by the movable vehicle for connecting said dynamo-electric machine to said transforming means.

4. In a regenerative system, a combination-machine located at a fixed point and connected to a normal source of power, means for connecting said combination-machine to the motor or motors carried by a car or train, said motor or motors being driven by the momentum of the car or train and generating a continuously-diminishing electromotive force as the car or train is being brought to a standstill, electrically-operated means for varying inversely and simultaneously the fields of the combination-machine so that the continually-diminishing electromotive force impressed upon it will be converted into a practically 45 constant electromotive force counter to and greater than the electromotive force of the normal source of power.

5. In a regenerative system, a dynamo-electric machine carried by a moving body and 55 operated by the momentum of said moving body, a combination-machine located at a fixed point and capable of receiving the electromotive force generated by said dynamo-electric machine and of transforming it into an electromotive force of higher potential, and means consisting of contact-shoes carried by said moving body, and fixed rails for completing the circuit through said dynamo-electric machine and said combination-machine.

65 6. In a regenerative system, a dynamo-electric machine carried by a moving body and operated by the momentum of said moving

body, a combination-machine located at a fixed point and capable of receiving the electromotive force generated by said dynamo-electric machine and of transforming said electromotive force into an electromotive force of higher potential, said combination-machine being so connected as to maintain the field of said dynamo-electric machine practically constant. 70 75

7. In a regenerative system, a dynamo-electric machine carried by a moving body and operated by the momentum of said moving body, a combination-machine located at a fixed point, and consisting of three machines 80 the armatures of which are connected in series and mechanically coupled together, two of said machines being adapted to transform the electromotive force generated by said dynamo-electric machine into an electromotive 85 force of a higher potential, and the third machine of said combination being adapted to maintain the field of said dynamo-electric machine practically constant and independent of the electromotive force generated by 90 its armature.

8. In a regenerative system, a combination-machine located at a fixed point and connected to a normal source of power, means for connecting one element of said combination-machine to a source of continuously-diminishing electromotive force located on a movable vehicle, electrically-operated means for inversely varying the fields of the combination-machine so that the counter electromotive force of one element of said machine will be maintained at a slightly lower potential than that of the continually-diminishing electromotive force impressed upon it and so that the electromotive force produced by the other element of said combination-machine will be slightly greater than and counter to that of the normal source of power. 95 100 105

9. In a regenerative system, a combination-machine located at a fixed point and connected to a normal source of power, means for connecting one element of said combination-machine to a source of continuously-diminishing electromotive force located on a movable vehicle, means for inversely varying the fields of the combination-machine, so that the counter electromotive force of one element of said machine will be maintained at a slightly lower potential than that of the continuously-diminishing electromotive force impressed upon it and so that the electromotive force produced by the other element of said combination-machine will be slightly greater than and counter to that of the normal source of power, means carried by said movable vehicle for controlling the operation of said field-varying means, and means comprising fixed rails, and contact-shoes carried by the car for connecting said field-varying means with said controlling means. 110 115 120 125 130

10. The combination of a controlling-switch located at a fixed point, means for operating said controlling-switch, means located on a movable vehicle for controlling said operat-

ing means, and means consisting of a shoe or shoes carried by said movable vehicle and a fixed rail or rails with which said shoe or shoes contact for completing the circuit through said controlling-switch-operating means and said controlling means.

11. The combination of a controlling-switch located at a fixed point, means for turning the arm of said controlling-switch in one direction, 10 said means comprising a motor connected in series with a magnetic clutch mounted in the arm of said controlling-switch, means mounted on a movable vehicle for controlling the operation of said motor and magnetic clutch, 15 and means for mechanically and automatically returning said controlling-switch arm to its normal position when said clutch becomes inoperative.

12. The combination of a composite machine located at a fixed point, a controlling-switch for varying inversely the fields of said composite machine, means for operating said controlling-switch, and means located on a movable vehicle for controlling said operating means.

13. The combination of a composite machine located at a fixed point, a controlling-switch for varying inversely the fields of said composite machine, means for turning the 30 arm of said controlling-switch in one direction, said means being controlled from a point on a movable vehicle, and separate and independent means for automatically returning said controlling-switch arm to its normal position.

14. In a regenerative system, a combination-machine located at a fixed point, means for varying inversely the fields of said combination-machine, means controlled from a point 40 on a movable vehicle for operating said field-varying means in one direction, and separate means for automatically restoring said field-varying means to its normal position when said last-mentioned operating means becomes inoperative.

15. In a combination-machine, three armatures mechanically connected together, means for varying inversely the fields in which two of said armatures operate, and means for 50 maintaining the field in which the third armature operates practically constant.

16. The combination of a motor operated from a constant-potential circuit, and means for controlling said motor consisting of a plurality 55 of dynamo-electric machines having their armatures connected in series across the circuit-mains and mechanically coupled together, means for varying inversely the fields of two of said dynamo-electric machines so as to vary the electromotive force impressed 60 across the armature-terminals of the motor, the field-winding of said motor being independently connected to another of said dynamo-electric machines so as to maintain the 65 field of said motor practically constant.

17. In a regenerative system, a plurality of fixed conductors located parallel to the line of

travel of a moving vehicle and connected to a dynamo-electric power-translating device, a plurality of motors carried by a movable vehicle, and means carried by said moving vehicle for connecting the armatures of said motors in parallel across said fixed conductors and for connecting the fields of said motors in parallel between one of said conductors and ground.

18. In combination, a composite dynamo-electric machine comprising a plurality of elements having their armatures connected in series across a source of supply and having 80 their fields arranged to be inversely varied, one or more motors operatively connected to a load, means for electrically connecting said motors to one of the elements of said composite machine, and electrically-operated 85 means for gradually increasing or decreasing the field strength of the element to which the motors are electrically connected and simultaneously and inversely varying the field of another element of the said composite machine.

19. In an electric-railway system, a source of supply, a composite machine comprising a plurality of elements having their armatures connected in series across said source, a switch 95 operatively connected to the field-windings of said elements in such a manner that by the operation of the switch the fields of two elements will be simultaneously and inversely varied, a motive device for operating said 100 switch, a car or train equipped with one or more propelling-motors, means including switch-contacts on the car or train and a contact shoe or shoes engaging a conductor or conductors along the roadway for connecting 105 the propelling-motors across the terminals of one of the elements of said composite machine having a variable field, and additional means comprising switch-contacts on the car and a contact-shoe engaging a conductor along the 110 roadway for controlling the operation of said motive device.

20. In an electric regenerative system, a source of supply, a dynamo-electric machine connected on one side to said source and 115 adapted to transfer energy either from or to the source of supply, a car or train equipped with one or more propelling-motors, means including a conductor or conductors along the roadway and a contact shoe or shoes carried 120 by the car or train for electrically connecting the said motors to said dynamo-electric machine, a regulating device for the said dynamo-electric machine constructed and arranged to vary the electromotive force on the 125 side of the machine to which said motors are connected, a motive device for operating said regulating device, and means comprising a conductor along the roadway and a contact-shoe carried by the car or train for controlling 130 the operation of said motive device.

21. In a regenerative system, a moving body, a motor or motors carried by said moving body, means for connecting said motor or

motors to act as generators, a power-translating device located at a fixed point on the line of travel of said moving body capable of transforming the gradually-diminishing electromotive force produced by said motors acting as generators into a practically constant electromotive force, a field-regulating device for said power-translating device, a motive device for operating said regulating device, and means comprising a rail located at said fixed point and a contact-shoe carried by said moving body for controlling the operation of said motive device.

22. In combination, a source of current-supply, a dynamo-electric power-translating device located at a fixed point and adapted to transfer energy to or from said source of supply, a car or train equipped with one or more propelling-motors, an auxiliary dynamo-electric machine for maintaining the fields of said motor or motors practically constant, a regulating device for the said dynamo-electric power-translating device, a motive device for operating said regulating device, and means comprising a conductor along the roadway and a contact-shoe carried by the car or train for controlling the operation of said motive device.

23. In combination, a source of current-supply, a dynamo-electric power-translating device and an auxiliary dynamo-electric machine located at a fixed point, a car or train equipped with one or more propelling-motors, a regulating device for said dynamo-electric translating device, a motive device for operating said regulating device, means for controlling said motive device located on said car or train, and means comprising conductors along the roadway and contact-shoes carried by the car or train for connecting said propelling-motors to said power-translating device, the fields of said motors to said auxiliary dynamo-electric machine, and the means

for controlling the motive device to said motive device respectively.

24. In combination, a moving body, a motor or motors carried by said moving body, means for connecting said motor or motors to act as generators, a dynamo-electric power-translating device located at a fixed point and capable of receiving the gradually-diminishing electromotive force generated by said motors acting as generators and transforming it into a practically constant electromotive force, a regulating device for said dynamo-electric translating device, an electric motive device for operating said regulating device, and means comprising a conductor or conductors located at said fixed point and a contact shoe or shoes carried by said moving body for controlling the operation of said motive device.

25. In combination, a source of current-supply, a dynamo-electric power-translating device located at a fixed point and adapted to transfer energy either to or from the source of supply, a car or train equipped with one or more propelling-motors, means including a conductor or conductors along the roadway and a contact shoe or shoes carried by the car or train for electrically connecting the said motors to said dynamo-electric translating device, an auxiliary dynamo-electric machine located at said fixed point for maintaining the fields of said motor or motors practically constant, and a conductor or conductors along the roadway and a contact shoe or shoes carried by said car or train for connecting said auxiliary dynamo-electric machine with said motor-fields.

In witness whereof I have hereunto set my hand this 28th day of March, 1902.

ALBERT G. DAVIS.

Witnesses:

BENJAMIN B. HULL,
HELEN ORFORD.
